Primary Examiner — Andrew Kerr(74) *Attorney, Agent, or Firm* — Steven A. Nielsen; www.NielsenPatents.com(57) **CLAIM**

The ornamental design for a surgical water pitcher, as shown and described.

DESCRIPTION

FIG. 1 is a top and side perspective view of a surgical water pitcher showing our new design;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof; and,

FIG. 8 is a cross-section view thereof taken from line 8-8 in FIG. 6.

The broken lines in the drawings depict portions of the surgical water pitcher that form no part of the claimed design.
